UNITED STATES PATENT OFFICE.

EDWARD J. FROST, OF PHILADELPHIA, PENNSYLVANIA.

DESIGN FOR A COLLAR-BOX.

Specification forming part of Design No. **7,505**, dated June 30, 1874; application filed June 3, 1874.
[Term of Patent 3½ years.]

To all whom it may concern:

Be it known that I, EDWARD J. FROST, of Philadelphia, State of Pennsylvania, have invented a Design for a Collar-Box, of which the following is a specification:

The nature of my design is fully represented in the drawings, to which reference is made.

The collar-box is made to represent a drum. Figure 1 shows the top side of the drum; upon it there is engraved a representation of two drum-sticks, B. Fig. 2 shows the side of the drum, having broad bands A A, connected

by cords c; each of the cords has tightening-clips d upon it. Fig. 3 shows the bottom of the drum, having an imitation of cords, E, stretched across.

I claim—

A collar-box having the form and outline and ornamentation representing a drum, as herein shown.

EDWARD J. FROST.
